UNITED STATES PATENT OFFICE.

KENNETH RUSHTON, OF PHILADELPHIA, PENNSYLVANIA, ASSIGNOR TO BURNHAM, WILLIAMS & COMPANY, OF PHILADELPHIA, PENNSYLVANIA, A FIRM CONSISTING OF GEORGE BURNHAM, WILLIAM P. HENZEY, JOHN H. CONVERSE, WILLIAM L. AUSTIN, SAMUEL M. VAUCLAIN, ALBA B. JOHNSON, AND GEORGE BURNHAM, JR.

TRUCK.

SPECIFICATION forming part of Letters Patent No. 690,321, dated December 31, 1901.

Application filed September 12, 1901. Serial No. 75,179. (No model.)

To all whom it may concern:

Be it known that I, KENNETH RUSHTON, a citizen of the United States, residing in Philadelphia, Pennsylvania, have invented certain 5 Improvements in Trucks, of which the following is a specification.

My invention relates to certain improvements in trucks, especially those to be placed under electric locomotives and cars.

10 The object of my invention is to make the truck from merchant plate, so as to reduce the cost of manufacture and at the same time to make a substantial and easily-riding truck. This object I attain as hereinafter set forth, 15 reference being had to the accompanying drawings, in which—

Figure 1 is a side view of my improved truck. Fig. 2 is a plan view of one-half of the truck, and Fig. 3 is a transverse sectional 20 view of the same.

A is the frame of the truck. This frame consists of two side bars A', made of merchant plate, and cross-bars A² at each end, also preferably made of merchant plate, bent and bolted to the side bars, as shown. I preferably use for the side bars steel plates rolled to the proper thickness and of an even width, although in some instances they may be made 25 of sheet-steel cut to shape.

30 B is a metallic cross-frame extending from one side plate A' to the other across the center of the truck. This frame B has flanges b at each end, which are secured to the side plates A' by bolts c. The quadrangular frame 35 made up of merchant plates is substantial, rigid, and economical.

E is the spring-plank, hung from the cross-frame B by links e e, and supported on this spring-plank are coiled springs F, carrying 40 the bolster G, which is guided in the frame B in the usual manner. On this bolster is the usual center plate.

The side plates A' are cut out at a, and secured thereto are the pedestal-castings D. 45 In these pedestal-castings are mounted the usual boxes d, in which are journaled the axles of the wheels of the truck.

It will be noticed in referring to Fig. 3 that the pedestal-castings are secured to the out-

side of the truck-frame. The object of this 50 construction is to allow for the placing of the springs H H on the outside of the truck-frame and yet be directly above the boxes d, which are guided in the pedestal-castings D. These 55 springs are the ordinary type of elliptical springs, the center strap of each spring resting upon its box d, while the ends of the springs rest within loop-shaped brackets I, made in the present instance of wrought metal and secured to the side frame by bolts. 60 (Clearly shown in Fig. 3.)

By the construction above described I can use elliptical springs, so as to obtain ease of action and yet have sufficient room between the side plates of the truck for the brake 65 mechanism and motors.

I claim as my invention—

1. The combination in a truck, of the side plates of an even width throughout, and end plates secured thereto, a cross-frame secured 70 to the side plates, the whole forming a rigid truck-frame, said side plates being recessed, pedestal-castings secured to the outside of the frame at the recesses, boxes in the pedestal-frames, and springs mounted above the pedestal-frames and bearing upon the boxes, substantially as described.

2. The combination in a car-truck, of a frame having side plates made of metal of an even width throughout, transverse end plates 80 secured to the side plates, and a central transverse frame secured to the side plates, pedestals secured to the outside of the said side frames, boxes in said pedestals, projecting brackets secured to the side frame at each 85 side of each pedestal, and elliptical springs having their ends resting against the brackets and their centers resting upon the boxes, substantially as described.

3. The combination in a car-truck, of side 90 plates quadrangular in cross-section, end plates secured to the side plates forming the quadrangular frame, a transverse frame having wide flanges at each end, said flanges secured to the side plates of the truck-frame, 95 pedestals secured to the outside of the said side plates, the frame being notched between the pedestals, journal-boxes mounted in the

pedestals outside the side frame, springs mounted on the outside of the frame and resting on the boxes, a spring-plank, links connecting said spring-plank with the cross-frame, and a bolster carried by the plank, substantially as described.

In testimony whereof I have signed my

name to this specification in the presence of two subscribing witnesses.

KENNETH RUSHTON.
